PUZZLE

William Meagher Costigan, Grand Falls,
New Brunswick, Canada

Application August 2, 1934, Serial No. 738,145

2 Claims. (Cl. 273—132)

This invention relates to puzzles and an object of the invention is to provide a puzzle combination which will be interesting and can be made as difficult as desired by employing a plurality of fixed units and a series of movable units placeable having regard to the fixed units.

A further object of the invention is to provide a puzzle of this character which may take various forms.

10 A still further object of the invention is to provide a puzzle of this character which is worked out on a board or the like on a square figure subdivided into a plurality of spaces, the number of different species of unit employed corresponding to the number of spaces along a side of the square.

15 A further object of the invention is to provide a device of this character which may be readily and economically manufactured and marketed in very attractive form.

20 With these and other objects in view the invention will be apparent in the following specification and drawing.

In the drawing, Figure 1 is a plan view of the puzzle base divided into a plurality of spaces and bearing the units employed to work out the puzzle, the fixed units being shown in full lines and the movable units in dotted lines.

Figure 2 is a plan view of the base similar to Figure 1 showing a different type of unit.

25 Figure 3 shows a different type of base in which the fixed units are shown in full lines and the movable units in dotted lines.

Figure 4 is a view similar to Figure 3, illustrating a smaller base and a lesser number of pieces.

30 Figure 5 is an enlarged view of one type of unit that may be employed, such as illustrated in Figure 2.

Figure 6 is an enlarged detail of another type of unit which may be employed.

35 Figure 7 is an illustration of one general manner in which the fixed units may be held firmly upon the base.

Referring to the drawing, and more particularly to Figures 1 and 2, A indicates a suitable base for the puzzle, preferably being in the form of a game board or the like which is marked off into a plurality of series of zones intersecting one another. For instance, 10 indicates a series of horizontal zones, 11 a series of vertical zones and 12 indicates a diagonal zone extending from one corner of the board to the other. These zones are all formed by intersecting lines 13 or the like and the intersection of said zones produces a plurality of spaces 14.

50 The puzzle units are indicated generally by the

numeral 15 and comprise a series of fixed units 16 and a series of movable units 17. These units are employed in a series and each series is differentiated from the other by a value such as the colour, a numerical value or configuration. In other words, each series differs from any other series by visible physical characteristics.

According to the invention the number of any one series of units corresponds to the number of spaces 14 along any one side of the board. For instance, in Figure 1 seven spaces occur along any one side of the board and accordingly there are seven series of units, each series consisting of seven pieces which are all of one colour, in case colour is employed, or of the same shape, if shape is the defining factor, or in the case where numerals or words are employed, these defining characteristics are the same in one series, each series differing from the other.

The fixed units 16 are placed in a desired arrangement, having regard to how difficult a puzzle it is desired to provide and can be arranged so as to form one solution only, as in the case of the illustration in Figures 1 and 2, Figure 1 indicating the placement of the fixed pieces 16 and the movable pieces with the complete solution of a given puzzle based on colour value, and Figure 2 indicating the solution of a puzzle with pieces or units defined by a numerical value.

In the case of Figure 2 it will be seen that there are six spaces along each side of the board and the number of pieces in one series is six, there being a series of six 1's, six 2's, etc. up to six 6's.

According to the invention the units are placed so that each unit placed in a space on the board in a given zone must be different from any other unit placed in a space common to the same zone. In other words, through the related intersecting series of zones, the units placed in the spaces thus formed are not repeated in any one zone. On referring to Figure 1, it will be seen in the case of the first vertical zone on the left hand side, that a red unit occurs in the space 14 at the top of the zone. This happens to be a fixed unit 16. It is apparent, therefore, that a red unit cannot occur again in any of the spaces along this zone 11. Similarly it will be apparent that a similar unit cannot occur in the spaces along the upper horizontal zone 10 and the same is true in connection with the diagonal zone 12.

It is apparent, therefore, having regard to the placement of the fixed units 16, that a very difficult puzzle can be provided and in most cases a certain definite unit must be placed in each blank space to arrive at the correct solution.

This illustration is also clearly apparent in the case of Figure 2 where it will be seen that each space in each series of zones contains a unit of a given numerical value and such value is not repeated in any one zone no matter whether it is a horizontal band 10, a vertical zone 14 or the diagonal band 12.

In a modified form of puzzle the base A is circular or has a circular design thereupon which 10 is divided into a series of circular zones 18 intersected by a series of semi-circular zones 19 to form a plurality of spaces 20. In this case it will be clear that exactly the same principle is followed. Fixed units 21 occur in certain designated spaces 20 and movable units 22 are to be placed in spaces on the zones not occupied by fixed units. In each instance, upon examining the disclosure in Figures 3 and 4, it will be seen that each unit in any given zone is different from any other unit contained in the spaces on a common zone. This applies both to the circular bands 18 and the semi-circular zones 19.

In Figure 3 ten spaces 20 occur in each zone, both in the circular zone 17 and semi-circular 25 zone 18 and the number of units in each series is ten. In the case of Figure 4 eight spaces occur in any given zone and the number of units in each series employed is eight.

The values or physical characteristics of the 30 units employed in the various forms this puzzle may take may be, as previously indicated, defined by colour, numerical value, configuration or other suitable defining means. In Figure 6 I have illustrated a unit which may be defined by a word and by employing a series of units, each series being defined by a given word, and by relating the words a very interesting form of puzzle can be provided. For instance, a puzzle designed as a "depression" puzzle may be provided, the pieces 35 being arranged as described above and each series representing a factor which must be grouped to avoid an economic depression. This will serve along with the other illustrations to illustrate the wide application of the manner in which the units 40 or pieces may be designated.

The fixed units or pieces may be fixed in any suitable manner, it being the intention to provide a structure whereby pieces may be fixed on the

board in any desired space so that the puzzle may be varied. In Figure 7 a simple manner of fixing the piece is illustrated wherein a spike-like member 23 protrudes upwardly through the board A and into one of the pieces or units employed, the board being recessed as at 24 to receive the head of the spike-like member. This, however, is merely an illustration and any suitable means for fixing the units on the board may be employed.

Various modifications may be made in this invention without departing from the spirit thereof or the scope of the claims, and therefore the exact forms shown are to be taken as illustrative only and not in a limiting sense, and it is desired that only such limitations shall be placed thereon 15 as are disclosed in the prior art or are set forth in the accompanying claims.

What I claim as my invention is:—

1. A puzzle comprising a base marked off to provide a plurality of series of intersecting zones 20 defined by spaced apart lines, the intersection of said zones defining a plurality of spaces certain of said spaces bearing fixed visible units having definite surface characteristics, the remaining spaces being blank for receiving movable units whose 25 surface characteristics differ from any unit fixed or movable contained in a zone common to said remaining spaces, said movable units being placeable at will in any given blank space, the correct position of said units being governed by the fixed 30 units, said fixed units being preliminarily positioned to force one or more solutions.

2. A puzzle comprising a base carrying a square marked off to provide a plurality of series of intersecting zones defined by spaced apart lines, the 35 intersection of said zones defining a plurality of spaces, there being a corresponding number of spaces along each side of the square, certain of said spaces bearing fixed visible units having definite surface characteristics, the remaining 40 spaces being blank for receiving movable units whose surface characteristics differ in value from any unit fixed or movable in a zone common to said remaining spaces, said fixed units being selectively positioned in spaces at different points 45 on the base to force one or more solutions.

WILLIAM MEAGHER COSTIGAN.
